JAMES A. SEVEY, OF BOSTON, MASSACHUSETTS.

Letters Patent No. 105,498, dated July 19, 1870.

IMPROVEMENT IN MACHINE FOR SPLITTING WHALEBONE.

The Schedule referred to in these Letters Patent and making part of the same.

To all persons to whom these presents may come:

Be it known that I, JAMES A. SEVEY, of Boston, of the county of Suffolk and State of Massachusetts, have made a new and useful invention having reference to Machinery for Splitting Whalebone or other fibrous material of like character; and I do hereby declare the said invention to be fully described in the following specification, and represented in the accompanying drawing, of which—

Figure 1 is a top view.

Figure 2, a side elevation.

Figure 3, a front elevation.

Figure 4, a longitudinal section of a machine embodying the invention.

Figure 5 is a transverse section of it, the latter section being taken between its throat-piece adjusters.

The principal object of the machine is to effect the reduction of a strip of whalebone to two or more smaller strips, having rectangular or square transverse sections, and generally with parallel opposite sides.

In the drawing—

A denotes the standing frame of the machine, it being provided with two parallel arms B B, projected from and arranged so as to turn vertically on a shaft, C, extending through the posts of the frame.

Clamp-nuts *a a*, screwed on the shaft, serve, when screwed up against the arms, to force them up to shoulders of the shaft, and to thereby hold the arms in either a horizontal or inclined position, as may be desirable.

A bar, D, extends from one of the said arms to the other, and at its ends is securely fastened to the two.

Arranged parallel to the bar D is another such bar, E, which is suspended from the arms B B by means of vertical projections or ears *b b*, arranged to slide on the arms B B, and provided with clamp-bolts *c* and nuts *d* to fix them to the said arms.

There is a slot, *e*, in each of the arms, such slots being for reception of the bolts.

Between the two bars D E there are arranged two other such bars F G, each of which is provided with adjustments by which it may be moved at its ends, either toward or away from its fellow bar.

These adjustments consist, in part, of two slotted tenons or projections *f f*, which extend from each of the bars F G, and go through the next adjacent of the bars D E.

A clamp-screw, *s*, goes through a slot in each projection *f*, and screws into the next bar D or E, and serves to clamp the projection to the bar.

Circular passages are bored or formed through all the bars E F G H, to serve as bearings for the pairs of cylindro-segmental knife-carriers.

These knife-carriers are represented at I I'. Each is a cylindrical segment, nearly semi-cylindrical in shape, the versed sine of half the arc of its segmental section being equal to the radius of curvature minus one half the thickness of the knife to be held between each pair of these segments.

These knife-carriers, arranged within the circular passages or bearings of the bars D E F G, in manner as represented in the drawing, serve to support a series of knife-blades, K K, &c.

Each of these blades goes transversely through the said bars, and is supported on them by four of the carriers, the same being so that, by revolving the carriers more or less, the inclination of the blade transversely to the horizon may be varied and determined as circumstances may require.

To each pair of the carriers there is a clamp-screw, *h*, for holding the pair in position, such screw being screwed up into that bar D or E, within which the pair may be situated.

In Letters Patent No. 91,047, dated June 8, 1869, and granted to me, I have described and claimed analogous carriers, bearings, and clamps, for supporting and adjusting a knife for splitting whalebone.

By having the bar E movable, relatively to the bar D, I am enabled to adjust the guide-bar G at such distance from the guide-bar F as may be desirable, according to the width of the strip of whalebone to be operated on.

To each knife there is a throat-piece, L, which is a bar or rod of metal, it being arranged, with reference to the knife, in manner as represented. It goes through mortises made in the several bars D E F G, and is held in place by means of clamp-screws *i i*, screwed up into the bars, and against it.

To hold the throat-piece securely in place when the guide-bars F and G are made of wood, I employ thin plates or bars *k k*, of metal, fastened to the inner sides of the bars F G, and notched to receive the throat-pieces.

It was hereinbefore stated that each of the bars F G is provided with two slotted tenons or projections *f f*. They enter recesses *u u* in the ends of the bar.

Each tenon is connected to the bar by a screw, as shown at *t*.

By slackening or turning back one of these screws, and correspondingly tightening or setting up the other, an endwise movement may be imparted to the bar.

These endwise movements of the two bars are for

the purpose of moving the throat-pieces either nearer to or further from the knife-edges, as occasion may require.

The lateral adjustment of each of the bars F G is to enable it to be moved either toward or away from its fellow bar without the necessity of disturbing the clamp-screws, by which the knife-carriers and their knives are held in place.

Furthermore, there is a frame, M, arranged over the space between the guides F G.

This frame is pivoted to the middle of an adjustable cross-bar, N, so as to be capable of being turned in a vertical plane passing transversely through the machine.

The pivot of the frame M is shown at l.

The pivot may be arranged in a slot in the bar N, and may be provided with a clamp-nut, to fasten it in position in such slot.

The slot in such case should extend lengthwise of the bar, in order to enable the frame M, with the pivot, to be adjusted in directions lengthwise of the frame, in order to aid in effecting the proper adjustment of the pressure-rollers relatively to the knives.

The bar N has two slotted ears O O, which project back from it at right angles, and against two arms P P, which are pivoted to the shaft of the frame A, so as to be capable of turning vertically thereon.

Each of the arms P is furnished with a curved fork, Q, to embrace a clamp-screw, R, arranged in the next adjacent bar B, the whole being to enable the frame M to be adjusted and held in position relatively to the several knives, or at the proper distance therefrom, as circumstances may require.

The said frame M supports or carries a series of vertical slides, m, each of which is furnished with a helical spring, n, to press it downward, a screw, o, being employed, in manner as represented, in connection with the spring, to contract such spring, as occasion may require, in order to increase its elastic force.

To each of the said slides a wheel-carrier, p, is pivoted or hinged, in manner as shown in the drawing, the same being so as to enable the said carrier to swing in a plane longitudinally of the machine.

A roller or wheel, q, to revolve in a plane transversely of the machine, is arranged in and pivoted to each of the carriers p, there being one of such rollers to and over each of the knives.

By means of the application of the arms B B to the shaft C, so as to turn thereon, as described, we are enabled to readily invert the arms or turn them through a half circle, in order to conveniently gain access to the clamp-screws of the knives, and their carriers.

The clamp-screws of the throat-pieces also admit of each of the said throat-pieces being adjusted out of parallelism, or somewhat oblique to its knife, in order that the knife, while in operation, may be caused to separate from the strip of whalebone a strip which may be wedge-shaped.

On the lower bar of the frame M there is arranged a slide-bar, S, provided with ears a' a', extending down from it over and against the front edge of the said lower bar.

Clamp-screws b' b', going through slots in the ears, serve to clamp the slide-bar to the frame.

There are also adjusting-screws c' c' arranged in the end bars of the frame, and against the ends of the side bars, these screws being to effect a movement or adjustment of the bar endwise.

The bar S, shown in top view in Figure 6, is provided with a series of notches, d', to receive and guide the several slides m.

In the lower bar of the frame M, and below each

of the notches d', is a slot, e, of a size sufficient to allow the slide m to move laterally in either direction lengthwise of the frame M.

The bar S, with its adjusting-screws, serves to adjust the series of slide-bars, so as to move their pressure-rollers relatively to the knives.

In operating with the machine, the strip of whalebone to be separated into a series of strips is to be forced and drawn along between the guides F G, so as to be driven into contact with the series of knives.

The advancing end of the strip meets the cutting-edge of each knife in succession, and, as each strip is separated from the main piece, such strip will pass through the knife throat, and will finally drop out of the machine.

By putting together, side by side, a series of such strips, and running the whole, with their edges upward, through the machine, each of the strips may be divided into several smaller ones.

It should be understood, however, that while the strip is being operated on, the series of presser-wheels q is to be over and borne down upon the strip, so as to cause it to take the knives successively, and maintain its proper relation with each while it may be in operation.

Each of the throat-pieces, by being in the shape of a long rod, may, from time to time, be moved endwise, as it may become worn.

In this way a fresh or unworn portion of the throat-piece may be brought up the knife, as circumstances may require.

Each of the presser-wheels q, by being supported in a carrier, p, pivoted or hinged, as described, to a slide, m, is rendered capable of moving laterally more or less, to conform itself to the upper surface of the strip of whalebone. This is an important feature of the machine.

The thin plates or bars k k, fastened to the bars F and G by screws, not only perform the function of holding the throat-pieces securely in place, but they serve to enable the throat-pieces to be arranged at the proper distances apart, relatively to each other, to cause the bone to be cut smoothly, and in other respects as may be desired.

It is often the case that some parts of the bone, in order to be properly split, require the throat-pieces to be nearer the knives than is the case with other portions of the bone.

Thus it will be seen that, with a series of the plates k k, having their notches arranged for different grades of bone, so as to bring the throat-pieces into the proper relations with the knives, as each grade or quality of bone may require, we have an advantage which results from the employment of these plates.

I herein make no claim to anything, combination or arrangement of parts, as represented or described in the United States patent No. 70,545, dated November 5, 1867, meaning specially to make no claim to adjustable rollers, in combination with a series of knives and an adjustable throat-piece, as described in such patent. I employ, instead of rollers, rods or bars, so applied in the frame as not to be capable of revolving as rollers, though capable of being moved endwise, and being fixed therein, as and for the purpose hereinbefore explained.

In the above-described machine I claim as my invention, the following, viz:

In connection with the bars D E, when combined and arranged with a series of knives, substantially in manner as described, mechanism, as set forth, viz., the hangers b b, the slots e e, in the arms B B, and the clamp-bolts and nut c d, by which the said bar E may be adjusted and fixed in position, either nearer to or further from the bar D, as circumstances may require.

Also, the combination and arrangement of the throat-pieces, carriers F G, provided with the bars D E, and the series of knives K, applied to the latter.

Also, the combination and arrangement of the series of throat-pieces or bars L, made so as to be capable of being moved endwise, as and for the purpose described, with the series of knives K and the bars F G applied to the bars D E, as set forth.

Also, the combination of the additional throat-piece supporters k k with the main supporting and guide-bars F G applied to the bars D E, as described.

Also, the application of each presser-wheel q to its presser-bar or slide m, by means of the carrier p, pivoted to the said bar, substantially in manner and so as to operate as described.

Also, the combination of the bars D E with the frame or standard A, by means of the arms B B, pivoted to the said frame or its shaft, the same being for the purpose as specified.

Also, the application of the presser-roller frame M to its support-bar N, so as to be capable of being inclined relatively to the knives, as set forth.

Also, the combination and arrangement of the notched bar S and its adjusting screws, or their equivalents, with the frame M and its series of pressure-roller sliders m, as described.

J. A. SEVEY.
